UNITED STATES PATENT OFFICE

HARCOURT F. GADE, OF BROOKLYN, NEW YORK

ELECTRICAL TARGET TOY

Application filed June 15, 1928. Serial No. 285,552.

This invention relates to a game or toy for target practice and has special reference to the provision of an electrical target game or toy.

5 The prime object of my present invention centers about the provision of a portable electrically operable target game or toy designed and constructed so as to be capable of being manufactured and sold at an exceedingly low cost and embodying a structure which may be handled, set up and operated for target practice by the child with great convenience and ease.

To accomplish this prime object of the 10 invention, the invention includes the provision of a target toy embodying a support for the target elements which is adapted to form a stand for the toy and a carton or container for housing all of the operative 15 elements thereof; the further provision of a target toy in which there is provided a simply organized electrical signal circuit common to a plurality of target elements and operated to produce a signal when any 20 of the targets is struck; and the further provision of a target toy of this character in which all of the electrical parts are conveniently mounted on and within the casing stand therefor in a manner to permit ease 25 of assembly in the process of manufacture and efficient operation and accessibility in use.

To the accomplishment of the foregoing and such other objects as will hereinafter 30 appear, my invention consists in the elements and their relation one to the other, as hereinafter more particularly described and sought to be defined in the claims; reference being had to the accompanying drawings 35 which show the preferred embodiments of my invention, and in which:

Fig. 1 is a front elevational view of the 40 electrical target toy of my invention;

Fig. 2 is a view thereof taken on an enlarged scale in cross section in the plane of the line 2—2, Fig. 1, and showing the toy 45 in setup condition;

Fig. 3 is a cross sectional fragmentary view thereof taken on an enlarged scale in 50 the plane of the line 3—3, Fig. 1;

Fig. 4 is a rear elevational view of the target toy with parts removed;

Fig. 5 is a fragmentary view of a modified form of the invention; and

Fig. 6 is a fragmentary cross sectional view taken in the plane of the line 6—6, Fig. 5.

Referring now more in detail to the drawings and having reference first to Figs. 1 to 4 thereof, the electrical target toy of my present invention is shown to comprise a portable support in the form of a container generally designated as A and an electrical 60 65 70 75 80 85 90 95 100

operated target apparatus generally designated as B mounted in and housingly contained by the said container support A.

The supporting container A preferably comprises an elongated rectangular shaped carton made of two sections, a front section a' on which are mounted all of the parts which comprise the electrical target equipment, and a rear section a² which forms a closure for the front section a' and which is provided with a collapsible supporting stand a³. These carton sections a' and a² are preferably flanged members which telescope, as shown in Fig. 2 of the drawings, to form the complete carton and stand for the target toy, access to the interior of the carton being had by moving the sections out of telescoping relation. The collapsible stand a³ comprises a pair of wings 10 which are movable from a position flat against the vertical wall of the carton section a², as shown in Fig. 1 of the drawings, to a stand forming position at right angles thereto, as shown in Fig. 2 of the drawings, the said wings 10 being held in the stand forming position by means of a bendable flap 11 which interlocks with the edge walls 12 of cutout portions 13 formed in each of said wings, the said wings 10 and flap 11 being preferably made of a single sheet of material, the body of which is attached to the wall of the carton section a² by means of rivets or eyelets 14, 14. By means of this construction I provide a flat container or package for all of the operative parts, which may be readily set up as a stand for the target toy.

The target apparatus B comprises one or a plurality of target elements 15, 15 movably mounted on the carton section a' and preferably on the front wall thereof and exposed at openings or windows 16, 16 formed in the front wall of the carton. Each of the target elements is preferably provided with the representation of a target object, such as a bird 17, and the different elements 10 15 may be given graded values represented by the numbers "5", "10" and "20" thereon. These target elements are mounted so as to normally assume an erect position as shown in Figs. 1 to 4 of the drawings, in which 15 position the target elements 15 form closures for the windows 16, the said target elements being mounted so as to automatically resume such erect positions after being struck with a missile which may, for example, be a projectile of a pop gun or the like.

The target apparatus B further includes an electrical signal equipment which is actuated or operated when a target element is struck, this electrical equipment comprising 25 a sounding element such as a bell 18 attached by means of the eyelets 19 to the rear face of the front wall of the carton section a' , and a holder for a one cell battery, said holder comprising a pair of sections 21 and 30 22 also eyeleted to the front wall of the casing, the said sections being each formed with protruding resilient tongues as clearly shown in Figs. 2 and 4 of the drawings, which detachably receive the battery 20. 35 The signal element 18 and battery holder 21-22 are connected in a common circuit to each of the target elements 15, 15 by means of the conductors 23, 24 and 24' connected to the support for the target elements 40 in a manner to be described presently.

For producing an exceedingly simple organization of parts, I mount each of the target elements 15, 15 on means which forms a common portion of the operated circuit, the 45 mounting being such that the target element normally assumes an open circuit position, automatically resumes said open circuit position after being struck, and is actuated momentarily to a circuit closing position upon 50 being struck. This I accomplish by providing a rod conductor 25 which may be affixed to the front wall of the carton as by means of cotter pins 26 or the like, the said rod conductor forming a hinge structure or pintle 55 for each of the targets 15. Each of the targets 15 preferably comprises a plate formed of sheet metal and provided with integral trunnion elements 27, 27, all of which are received by the rod conductor 25 and 60 make electrical contact therewith. The trunnion elements 27 are so positioned as to cause the target elements 15 to normally gravitate to the vertical positions best shown in Fig. 3 of the drawings, and so that the rear face 65 thereof which is provided with a thin insu-

lating coating 28 is in contact with a second rod conductor 29 affixed, as by pins 30, to the carton front wall and arranged parallel with the rod conductor 25. The rod conductors 25 and 29 are connected to the conductors 23 and 24' in any desired way as by means of the eyelets 31 and 32, which serve to affix these conductors to the front wall of the casing A.

The electrical signal circuit is common to each of the target elements, the construction being such that when a target element is struck, the electrical circuit is closed for sounding the signal thereof. To this end each of the metallic target elements 15 is provided with a contact member or element 33 which may be soldered as at 34 to the rear face of the target plate (see particularly Fig. 2), the said contact element being movable with the target element 15, when the latter is struck, from the full line position to the dash dotted line position shown in Fig. 3 of the drawings, the engagement between the contact element 33 and the rod conductor 29 as shown in Fig. 3 of the drawings, resulting in the closing of the signal circuit. After a target is struck and the signal circuit is closed, the target element 15 will automatically return by gravity to its normal position, resulting in a breaking or opening of the circuit, the signal element 18 being thus momentarily actuated for indicating that a hit has been made. It will be noted that the second rod conductor 29 defines a limiting stop for the movement of the target plate 15 in both of its opposite directions and defines a conductor and contact element mating with the contact elements 33 in the circuit closing position of the latter.

In the modification of the construction shown in Figs. 5 and 6 of the drawings, the target elements 15', 15' are mounted on the common conductor and hinge pintle support 25' in a way to permit a complete movement of rotation of the target element when the same is struck by a missile or projectile. Accordingly, the second rod conductor 29, shown in Figs. 1 to 4 of the drawings, is eliminated; and circuit closing contact is provided by the engagement of an edge wall 35 of a target element with a resilient contact 36 projecting into the locus of movement of the target element, as clearly shown in Figs. 5 and 6 of the drawings. The mounting of the target elements on the conductor 25' provides one connection to the electrical circuit and the contacts 36 connected to conductors 37, 37 by being eyeleted thereto and to the front wall of the carton section a' as at 38, 38 provide the other connection to the electrical signal circuit.

The manner of making and using the target game of my present invention and the many advantages thereof will in the main be fully apparent from the above detailed de-

scription thereof. It will be seen that the support A provides a stand for the target which may be readily set up by the child into the condition shown in Fig. 2 of the drawings, and also provides a flat collapsible package and portable container, as shown in Fig. 1 of the drawings, for holding and housing all of the parts of the target apparatus. It will be further seen that the electrical equipment comprises only a bell and battery holders and simple conductive connectors, all common to a plurality of target elements, the design and construction being such that an exceedingly simple organization of parts is provided. It will be further seen that the method of mounting the target elements is not only a factor in producing a simplified construction capable of being manufactured at a low cost, but is a factor in permitting the same to be readily handled, operated and understood by a child. The mounting of all of the parts on one wall of the container produces a simple assembly and permits ready inspection of the parts when the carton or container is opened by the simple process of separating the two sections of the container. By the method of attaching the parts of the electrical equipment to the casing wall, I am enabled to build a carton of inexpensive material, such as hard cardboard of the like, the same forming an insulating medium between the parts of the electrical circuit. The provision of a simple two part battery holder attached to such a casing is also an important feature of this construction.

While I have shown and described my invention in the preferred forms, many changes and modifications may be made in the structure disclosed without departing from the spirit of the invention, defined in the following claims.

What I claim is:

1. An electrical target toy comprising a wall, a plurality of target elements, means including a common hinge pintle for mounting all of said target elements on said wall, a battery holder, a common signal element and conductors forming a complete signal circuit with any of said target elements located on said wall, said common hinge pintle forming one of the conductors of the circuit, and means actuated by movement of any of said target elements about the hinge pintle when struck for closing said signal circuit and operating said common signal element.

2. An electrical target toy comprising a casing, a target element movably mounted on said casing, electrical equipment forming a complete signal circuit with said target element and arranged within said casing, said target element being mounted on said casing to normally assume an open circuit position and to automatically resume said

open circuit position after being struck, and means actuated by movement of said target element when struck for momentarily closing and operating said signal circuit.

3. An electrical target toy comprising a hinge support, a plurality of target elements mounted on said hinge support, electrical equipment forming a complete signal circuit with said target elements, said hinge support forming a conductor for said circuit, said target elements being mounted on said hinge support to normally assume an open circuit position and to automatically resume said open circuit position after being struck, and means actuated by movement of said target elements when struck for momentarily closing and operating said signal circuit.

4. An electrical target toy comprising a supporting wall, a plurality of windows in said wall, a hinge support on said wall, a plurality of target elements mounted on said hinge support at said windows, a battery holder, a signal element and conductors forming a complete signal circuit with any of said target elements mounted on said wall, said common hinge support forming a common conductor for said circuit, the said target elements being mounted on said hinge support to normally assume an open circuit position and to automatically resume said open circuit position after being struck, and means actuated by movement of any of said target elements when struck for momentarily closing and operating said signal circuit.

5. An electrical target toy comprising a flat casing of small depth, a plurality of windows in the large front wall of said casing, a hinge support on said casing wall, a plurality of target elements mounted on said hinge support at said windows, a battery holder, a signal element and conductors forming with any of said target elements a complete signal circuit located within said casing, said hinge support forming a conductor for said circuit, the said target elements being mounted on said hinge support to normally assume an open circuit position and to automatically resume said open circuit position after being struck, means actuated by movement of any of said target elements when struck for momentarily closing and operating said signal circuit, and a collapsible supporting stand mounted on the large rear wall of said casing for holding the casing and target means in an upright position when in use, and for holding flat against the casing wall when not in use.

6. An electrical target toy comprising a supporting wall, a plurality of windows in said wall, a common hinge support on said wall, a plurality of target elements mounted on said hinge support at said windows, a battery holder, a signal element and con-

ductors forming a complete signal circuit with any of said target elements mounted on said wall, said common hinge support forming a common conductor for said circuit, the said target elements being mounted on said hinge support to normally assume an open circuit position and to automatically resume said open circuit position after being struck, and means actuated by movement of any of said target elements when struck for momentarily closing and operating said signal circuit, said means including a bar on said wall forming a stop for the target elements in their open circuit positions and forming a contact conductor for the target elements in their closed circuit positions.

7. An electrical target toy comprising a wall, a plurality of windows in said wall, a common hinge pintle support on said wall, a plurality of target plates mounted on said hinge pintle support at said windows, a battery holder, a signal element and conductors forming a complete signal circuit with any of said target plates fixed to said wall, said common hinge pintle support forming a common conductor for said circuit, the said target plates being mounted on said hinge pintle support to normally assume an open circuit position and to automatically resume said open circuit position after being struck, and means actuated by movement of any of said target elements when struck for momentarily closing and operating said signal circuit, said means including a conductor in the path of movement of said target plates with which said target plates are adapted to make contact.

8. An electrical target toy comprising a casing made of an insulating sheet material, a plurality of windows in a wall of said casing, a common hinge support on said casing wall, a plurality of target elements mounted on said hinge support at said windows, a two-section battery holder, a signal element and conductors forming a complete signal circuit with any of said target elements mounted on said casing wall and located within said casing, said common hinge support forming a common conductor for said circuit, the said target elements being mounted on said hinge support to normally assume an open circuit position and to automatically resume said open circuit position after being struck, and means actuated by movement of any of said target elements when struck for momentarily closing and operating said signal circuit.

Signed at Brooklyn in the county of Kings and State of New York this 13th day of June, A. D. 1928.

HARCOURT F. GADE.
